(73) Assignee: **Starfish Software, Inc., Scotts Valley, CA (US)**

(57) **CLAIM**

(**) Term: **14 Years**

The ornamental design for a graphic user interface for an electronic device for a display screen, as shown and described.

(21) Appl. No.: **29/078,465**

DESCRIPTION

(22) Filed: **Oct. 27, 1997**

Related U.S. Application Data

(62) Division of application No. 08/905,463, filed on Aug. 4, 1997.

FIG. 1 is a perspective view of a graphic user interface for an electronic device for a display screen, the broken line drawing of a display screen is for illustrative purposes only and forms no part of the claimed design;

(51) **LOC (7) Cl. 14-02**

FIG. 2 is a front view thereof, the broken line drawing of a display screen is for illustrative purposes only and forms no part of the claimed design;

(52) **U.S. Cl. D14/488**

FIG. 3 is a front view thereof, the graphic user interface is shown separately for clarity of illustration, on an enlarged scale;

(58) **Field of Search D14/485-95; D18/24-33; D21/324-33; D20/11; D19/6; 345/326, 339-58**

FIG. 4 is a front view of a second embodiment thereof, the graphic user interface is shown separately for clarity of illustration, on an enlarged scale;

(56) **References Cited**

FIG. 5 is a front view of a third embodiment thereof, the graphic user interface is shown separately for clarity of illustration, on an enlarged scale, and,

U.S. PATENT DOCUMENTS

FIG. 6 is a front view of a fourth embodiment thereof, the graphic user interface is shown separately for clarity of illustration, on an enlarged scale.
